SODA SIPHON

Daniel C. Stewart, Astoria, Long Island, N. Y.

Application July 20, 1936, Serial No. 91,592

5 Claims. (Cl. 215—4)

This invention relates to soda water siphons and, among other objects, aims to provide a greatly improved, compact, easily refillable and light weight metal siphon for carbonated water 5 having an air chamber to prevent over-filling and resultant explosions of the container.

Other aims and advantages of the invention will appear in the specification, when considered in connection with the accompanying drawing, 10 wherein:

Fig. 1 is a central sectional view of a metal siphon embodying the invention; and

Fig. 2 is a sectional view taken on the line 2—2 of Fig. 1.

Practically all soda water siphons now on the market employ heavy glass bottles, the weight of the quart size being six pounds or more. The glass has to be of sufficient thickness to withstand the tremendous pressures created in the 20 bottles when the water is charged with carbon dioxide under high pressures. Some of the glass bottles are reinforced by woven strands of piano wire or the like to prevent accidents, due to explosions. Such glass bottles are naturally 25 subject to breakage and have caused many serious accidents. If they are accidentally or carelessly over-filled with water, the resulting pressure will be excessive and exceedingly dangerous. Moreover, the glass acts as a heat insulator and 30 prevents rapid cooling of the charged water. This invention, therefore, provides a compact metallic bottle made of thin sheet metal capable of withstanding enormous pressures and having provision to prevent over-filling as well as the 35 creation of excessive pressures which would cause explosions. Also, it provides a quart size container weighing only a fraction of the weight of the usual glass bottles. Further, the idea is to enhance the appearance of such bottles and to 40 provide a container which can be opened and easily cleaned by removing the siphon head and tube.

Referring particularly to the drawing, showing one practical embodiment of the invention, the 45 siphon container therein illustrated is composed of a non-corroding metal, such as Monel metal or stainless steel and is made in sections which are stamped out or otherwise formed and welded together. In this instance, the container is shown 50 as being generally cylindrical. It has a sheet metal base portion 10 secured to the rounded bottom portion of a lower container section 11. These two parts are preferably formed and welded, 55 brazed or otherwise secured together and, afterwards, secured to an upper container sec-

tion 12. The upper section 12 is shown as having an internal metal vase 13 conveniently brazed or welded to the lower edge thereof and spaced from the inside walls to provide an annular air chamber 14 between the vase and the outside wall. The lower portion of the vase has one or more openings 15 and the lower end of the section 12 is adapted to be telescoped within the upper end of the section 11 and the two sections welded or brazed together as shown. 10 The upper ends of the section 12 and the vase 13 present an opening for a metal screw threaded filling neck or plug 16 shown as being secured therein by means of a nut 17 within the vase screwed on a nipple extension 18 of the neck 15 and securely clamping the upper end of the vase to the top of the section 12. When the parts are thus secured, the entire bottom section 11 and the vase portion 13 constitute the water compartment; while the chamber 14 provides an air 20 pocket or chamber to prevent overfilling.

As is usual, the container is provided with an ordinary siphon tube 19 which carries a gasket 20 at its upper end engaging the mouth of the neck or plug 16 and adapted to be clamped thereon by a screw threaded, valved head 21 of the usual type. The head has provision for the insertion of the usual gas cartridge 22 in a holder 23, the arrangement being such that the cartridge is punctured by screwing the holder on a nipple 30 24 so that the gas will be discharged through the head and the siphon tube 19 into the container. Incidentally, the volume of the air chamber is shown as being about one-fourth of that of the water chamber or compartment. The CO₂ 35 cartridges or tubes contain about 8½ grams of gas at 1000 pounds pressure. When discharged into a container holding a quart of water with an air chamber of 8 ounces water displacement, the pressure in the filled container will be reduced to between 35 and 50 pounds, depending upon the amount of absorption of the gas by the water when the charge is completed and the contents well shaken.

In Fig. 1, the container has been filled with 45 water by removing and replacing the head 21 and tube 19 and is about to be charged with gas from the cartridge 22. The water rises only slightly in the air chamber 14 due to the static head above the opening 15. As the gas enters, the container 50 is shaken to hasten the gas absorption by the water and to cause the remaining free gas to enter the opening 15 and mix with the trapped air in the chamber 14. As the CO₂ is admitted it creates a gas pressure causing some of the water to enter 55

- the compression chamber compressing the trapped air in 14 which acts as a buffer. The volumes are such that the final compression pressure of the mixed air and gas in said chamber cannot exceed 5 approximately 50 pounds per square inch and preferably ranges between about 35 and 50 pounds, depending upon the amount of absorption of the gas by the water. This pressure is sufficient to discharge the entire contents from 10 the container and will never cause an explosion which would occur due to accidental or careless overfilling of an ordinary bottle.

While the air chamber or trap may be produced in various ways, the illustrative example 15 embodies probably the easiest and simplest form to manufacture. Furthermore, the shape of the container is such that it may be made of die-stamped sheet metal sections. Since the chamber 20 positively prevents overfilling the container and insures safe pressures, the sheet metal may be very thin. Hence, the weight is greatly reduced and the containers are much easier to handle.

Obviously, the present invention is not restricted to the particular embodiment thereof 25 herein shown and described. Moreover, it is not indispensable that all the features of the invention be used conjointly, since they may be employed advantageously in various combinations and sub-combinations.

30 What is claimed is:

1. A siphon container for charged water comprising a bottle composed of sheet metal sections secured together; an annular vase secured in the upper part of the bottle having an opening at 35 its lower end portion leading into the water compartment and providing an air chamber; and a screw threaded metal neck on the bottle removably to receive a siphon head.

2. A siphon container for charged water com-

prising, in combination, a metal bottle; a neck secured to the mouth of the bottle; a tubular member within the bottle projecting downwardly therein from the mouth and providing an air chamber in the upper portion of the bottle and communicating with the bottle near its lower end; and a siphon head having a combined filling and dispensing tube projecting through the neck into the bottom portion of the bottle.

3. A siphon container for charged water comprising, in combination, a sheet metal bottle; a neck removably secured to the mouth of the bottle; a tubular partition within the bottle secured at its upper end to said neck and providing an annular air chamber in the upper portion of 15 the bottle and communicating at its lower end portion with the interior of the bottle; and a siphon head having a filling and dispensing tube projecting through the neck into the bottom portion of the bottle.

4. A siphon container for charged water comprising, in combination, a metal bottle; an annular vase secured in the upper part of the bottle having an opening near its lower end portion 20 communicating with the water compartment and providing an air chamber; and a neck secured in the mouth of the bottle and having means clamping said vase to the bottle wall around the mouth.

5. A siphon container for charged water comprising, in combination, a substantially cylindrical 30 sheet metal bottle composed of sections; a sheet metal vase axially arranged within the upper portion of the bottle and secured to the inner wall thereof near a joint between two of said sections providing an air chamber communicating at its 35 lower end with the water compartment of the bottle; and a neck removably secured to the mouth of the bottle.
